UNITED STATES PATENT OFFICE.

HENRY W. HERRMAN AND CHARLES J. EVERETT, OF NEW YORK, N. Y.

PHOTOGRAPHIC-PRINTING APPARATUS.

SPECIFICATION forming part of Letters Patent No. 721,369, dated February 24, 1903.

Application filed November 14, 1902. Serial No. 131,289. (No model.)

To all whom it may concern:

Be it known that we, HENRY W. HERRMAN and CHARLES J. EVERETT, citizens of the United States, and residents of the borough 5 of Manhattan, in the city and State of New York, have invented a new and useful Improvement in Photographic-Printing Apparatus, of which the following is a specification.

This invention relates to an improvement 10 in photographic-printing apparatus, and has more particularly for its object to provide an apparatus in which printing-frames containing the sheets to be printed may be inserted into position upon opposite sides of an artificial light.

A further object is to provide an apparatus 15 of the above character in which large and consequently heavy printing-frames may be easily inserted and removed from their positions in front of the light.

A practical embodiment of this invention is represented in the accompanying drawings, in which—

Figure 1 represents the apparatus in front 20 elevation with upper and lower printing-frames on their respective tracks ready to be inserted in positions within the casing containing the artificial light. Fig. 2 is an enlarged vertical section from front to rear 25 through the apparatus, showing the upper and lower printing-frames within the casing exposed to the artificial light; and Fig. 3 is a partial top plan view of the apparatus, certain of the portions of the casing being removed to more clearly illustrate the locations 30 of the parts within the same.

A series of short front posts 1 and a series 35 of longer rear posts 2, suitably spaced apart by bars 3, support at their tops two longitudinal rails 4 and 5, forming a track along which the lower photographic-printing frame 6 is fitted to travel.

A pair of front and rear rails 7 and 8 are supported by a suitable framework 9 above 40 the track-rails 4 and 5, which rails 7 and 8 form an upper track along which a photographic-printing frame 10, similar to the printing-frame 6, is fitted to travel. The lower track 45 extends beyond the ends of the upper track 7 and 8 a distance sufficient to permit the lower printing-frame to be moved along

into a plane beyond the ends of the said upper track 7 and 8.

The lower printing-frame 6 comprises the frame proper and an exterior frame 11, in 55 which the frame proper is pivoted, so that the frame proper may be reversed on its axis to bring the back of the frame uppermost for the purpose of readily inserting and removing the sheets to be printed and the printed 60 sheets without removing the frame from the track. This outer frame 11 is provided with traction-wheels 12, preferably two on each side, which are fitted to travel along the rails 4 and 5 for readily moving the lower printing-frame along the said track. The upper printing-frame 10 is provided with track-wheels 13, preferably two on each side, which are fitted to travel along the track-rails 7 and 8 of the upper track for easily moving the upper frame along the said track. The upper 65 and lower frames are fitted to travel along their respective tracks with their transparent fronts facing each other.

An artificial light is located between the upper and lower tracks, so that the printing-frames 6 and 10 may be moved along their respective tracks into position upon the opposite sides of the said light. In the present instance the artificial light is shown as composed of a series of Crookes tubes 14, electrically connected to a circuit. (Not shown herein.) These tubes are supported near their front and rear ends in brackets 15 and 16, carried by longitudinal bars 17 and 18, carried 80 by the casing, to be immediately described. The tubes 14 are located within a suitable casing, the side walls 19 and 20 of which are supported by the framework which supports the tracks. These side walls 19 and 20 of the 85 casing are connected above the upper track 7 and 8 by a cover 21. A front wall 22 connects the front edges of the side walls 19 and 20 of the casing. A flue is formed at the rear end of the casing by a back wall 23 and a wall 24, 90 connecting the side walls 19 and 20. A transparent window 25 is placed in the front wall 22 of the partition for the purpose of examining the front ends of the tubes, and a transparent window 26 is placed in the rear wall 23 for use in examining the rear ends of the 95 said tubes. If desired, a sheet of colored

glass 27—such, for instance, as yellow glass—
may be inserted between the tubes and the
front of the frame. In the present instance a
sheet of this colored glass is shown between
5 the tubes and the upper printing-frame 10.
To protect the several parts of the casing from
becoming damaged by fire, because of the
great heat of the tubes, the interior of the
casing may be lined with asbestos 28 or other
10 heat-resisting material. To intensify the
light, the interior of the casing may be white-
washed, if so desired. The side walls 19 and
20 of the casing are cut away sufficiently to
permit the ready insertion and removal of
15 the upper and lower printing-frames.

When it is desired to use the apparatus, the
upper frame 10 is opened from the back and
the sheets to be printed and the sheets of sen-
sitized paper are inserted in the usual man-
20 ner therein. The lower frame is turned on
its pivoted connection to bring its back up-
permost. The sheets to be printed and the
sensitized paper are then inserted in the
frame and locked therein in the usual man-
25 ner. The frame 6 is then turned back to its
normal position, with its transparent front up-
permost. The two frames 6 and 10 are then
rolled into the casing upon opposite sides of
the artificial light and are left there a sufficient
30 time to produce the printing result desired.
The printing-frames may then be removed
from the casing from either side. The upper
frame is then opened to permit the removal
of the cards and the printed material. The
35 frame 6 is rolled along the lower track 4 5
until it is free of the upper track. The frame
is then reversed to bring its back uppermost,
so that the sheets and printed material may
be readily removed therefrom. To guide the
40 upper and lower printing-frames along the
tracks and to take off some of the train from
the traction-wheels, we may further provide
the sides of the said trains with rollers or
casters 29, which bear against the inner faces
45 of the track-rails 4 5 7 8.

It will be seen that by the use of the appa-
ratus hereinabove described we are enabled
to rapidly and easily produce photographic
printed copies and at the same time use very

large frames capable of printing a large num- 50
ber of copies at once, for the reason that the
frames are so supported that they may be
readily moved into and out of their exposed
position with respect to the light. Further-
more, by arranging the apparatus so that 55
prints may be taken upon opposite sides of
the light we are enabled to double the ordi-
nary capacity of an apparatus using a pre-
determined quantity of artificial light.

It is evident that changes may be made in 60
the construction, form, and arrangement of
the several parts without departing from the
spirit and scope of the invention. Hence we
do not wish to limit ourselves strictly to the
structure herein set forth; but 65

What we claim is—

1. A printing apparatus comprising an ar-
tificial light, two tracks passing upon oppo-
site sides of the light and printing-frames fit-
ted to be moved along the tracks into and out 70
of proximity to the light.

2. A printing apparatus comprising an ar-
tificial light, two tracks passing upon oppo-
site sides of the light, one of said tracks be-
ing extended beyond the other and printing- 75
frames fitted to be moved along the tracks
into and out of proximity to the light.

3. A printing apparatus comprising a cas-
ing, an artificial light therein, a track extend-
ing through the casing, and a printing-frame 80
fitted to be moved along the track into and
out of the casing.

4. A printing apparatus comprising a cas-
ing, an artificial light therein, two tracks
passing through the casing upon opposite 85
sides of the light and printing-frames fitted
to be moved along the tracks into and out of
the casing.

In testimony that we claim the foregoing
as our invention we have signed our names, 90
in presence of two witnesses, this 10th day of
November, 1902.

HENRY W. HERRMAN.
CHARLES J. EVERETT.
